DESIGN FOR A LADY'S SLIP OR SIMILAR ARTICLE

Irving Wasserman, Brooklyn, N. Y.

Application September 12, 1942, Serial No. 108,216

Term of patent 3½ years

To all whom it may concern:

Be it known that Irving Wasserman, a citizen of the United States and resident of Brooklyn, in the county of Kings and State of New York, has invented a new, original, and ornamental Design for a Lady's Slip or Similar Article, of which the following is a specification, reference being had to the accompanying drawing, forming part thereof, in which the sole figure is a front view of a lady's slip showing my new design. The back of the slip is conventional. The dot-and-dash lines represent conventional ornamentation, stitching, and shoulder straps.

The dominant features of the design are shown in full lines.

I claim:

The ornamental design for a lady's slip or similar article, substantially as shown and described.

IRVING WASSERMAN.
